UNITED STATES PATENT OFFICE.

WILKIE GREELEY FOWLER, OF WINNIPEG, CANADA.

CORNER GUARD OR PROTECTOR FOR TRUNKS.

SPECIFICATION forming part of Letters Patent No. 774,575, dated November 8, 1904.

Application filed May 19, 1904. Serial No. 208,755. (No model.)

To all whom it may concern:

Be it known that I, WILKIE GREELEY FOWLER, commercial traveler, of the city of Winnipeg, in the county of Selkirk, in the Province of Manitoba, Canada, have invented certain new and useful Improvements in Corner Guards or Protectors for Trunks, of which the following is a specification.

My invention relates to improvements in corner guards, protectors, or bumpers for trunks; and the object of the invention is to devise a simple and efficient device of this class which will have a maximum resiliency, so as to prevent the jar of a trunk when being thrown down in a corner from breaking or otherwise fracturing the trunk; and it consists, essentially, of a bracket having three branches to extend diagonally over the top corner and the adjacent side corners, an interior resilient filling of rubber or other suitable resilient material held within the aforesaid bracket, as hereinafter more particularly explained.

Figure 1 is a perspective view of a corner of a trunk provided with my improved protector. Fig. 2 is a substantially sectional plan.

In the drawings like letters of reference indicate corresponding parts in each figure.

A is the bracket, composed of three branches A², A³, and A⁴, secured at their ends to the trunk and extending outwardly at an acute angle from the sides thereof and ending in a projecting portion A', having a central opening a.

B is a resilient filling which extends throughout the inside of the bracket and also has a projecting portion b, which extends out through the opening a at the corner of the

bracket. Said portion b is of the same diameter as the opening, and consequently when the pressure is exerted against it it will recede into the opening and not have any tendency to cut, crack, or break.

C represents nail screw-bolts or other suitable fastening devices which extend through the branches of the bracket into the sides and top of the trunk, such nails extending through the resilient filling, as indicated.

It will now be seen that on account of the projection b being of rubber a maximum resiliency is provided, as such rubber extends right through the interior of the bracket and the resiliency extends, therefore, all underneath the bracket and no matter where the trunk may be struck on the corner the filling will yield to a maximum extent.

What I claim as my invention is—

The combination with the hollow bracket having branches to extend over the top and sides at the corner of a trunk, said branches extending outwardly at an angle to said top and sides and a central projecting portion having an opening therein, of a filling of resilient material, such as rubber extending underneath the bracket and throughout the same and having a projecting portion extending through the opening beyond the projections of the bracket, said projecting portion being of the same diameter as the opening and a fastening device for holding the branches of the bracket to the trunk as and for the purpose specified.

WILKIE GREELEY FOWLER.
